WINDOW SHADE STOP

Filed June 10, 1930

JACK C. STICH.

By Glenn O'Brien Attorney

UNITED STATES PATENT OFFICE

JACK C. STICH, OF NEW YORK, N. Y.

WINDOW SHADE STOP

Application filed June 10, 1930. Serial No. 460,173.

This invention relates to improvements in window shade stops. The primary object of the invention resides in a window shade stop which is mounted upon the inside of a window casing to limit the winding of the shade upon its spring roller to prevent the loss of its winding tension. Another object is to provide a shade stop which may be installed in pairs and respectively mounted opposite each other upon a window casing approximately on the same plane with the meeting rails of the upper and lower sashes to prevent accidental raising of the shade beyond its usual half-way position, the said stops being engaged by the cross strip at the lower marginal edge of the shade.

A further object is the provision of a shade stop through which the side edges of the shade slide during the movement of the shade, and which serves to guide the same during such movement.

A still further object is to provide a shade stop which is simple of construction, inexpensive of manufacture and which can be applied to window casings without marring or detracting from the appearance thereof.

With these and other objects in view, the invention resides in the certain novel construction, combination and arrangement of parts, the essential features of which are hereinafter fully described, are particularly pointed out in the appended claims, and are illustrated in the accompanying drawings, in which:

Figure 1 is a front elevational view of a window equipped with my improved shade stop.

Figure 2 is an enlarged detail vertical sectional view on the line 2—2 of Figure 1.

Figure 3 is a fragmentary vertical sectional view taken at right angles to Figure 2.

Referring to the drawings by reference characters, the numeral 10 designates a window casing of the conventional type which supports a spring actuated shade roller 11 at the top thereof, and on which the shade 12 is windable. It will be appreciated that

ofttimes the shade will accidentally move upward and wind about the spring roller 11, and which idle rotation tends to reduce the spring tension of the roller and which requires the removal of its roller from its bracket in order to reset the tension. My invention aims to prevent the accidental winding of the shade upon the roller and to guide the shade in its sliding movement.

My improved shade stop is designated by the reference numeral 13, and includes a disc-like body 14 which may be constructed of wood or other like material. The body 14 centrally thereof is provided with an opening 15 for the passage of a fastening element 16 in the nature of a screw or the like 16, whereby the shade stop may be fixedly attached to the inner side of the window casing 10. Extending outwardly from one of the flat faces of the disc like body 14 is an extension portion 17 which is semi-circular in end elevation as best seen in Figure 2 of the drawings. The extension portion 17 is slotted inwardly as at 18 from its outer end and which slot terminates at the adjacent flat face of the body 14.

In practice, my improved shade stops are used in pairs and are respectively mounted on the same horizontal plane on opposite sides of the window casing 10. In the present instance, these shade stops are mounted on a plane substantially the same as the plane of the meeting rails of the upper and lower sashes of a window although they may be mounted adjacent the top of the window casing as indicated in dotted lines in Figure 1 of the drawings. After the shade stops have been attached to the window casing by passing the fastening elements 16 through the openings 15 and screwing the same into the window casing, the opposite side edges of the shade 12 are flexed and inserted into the slots 18. It will therefore be seen that the shade 12 may have free vertical sliding movement, and be guided in its movement by the walls of the slot 18, and the raising of the shade is limited by reason of the fact that the cross strip at the lower marginal edge of the shaft 12 and indicated at 19 abuts the under side of the respective stops. In Figure 109

1 it will be noted that the shade cannot pass above the plane of the stop which serves to prevent accidental winding of the shade upon its roller. If for any reason it should be desired to fully wind the shade, the shade may be flexed to move the side edges out of the slots of the respective stops and then permitted to wind up. The stop devices as before stated prevent the accidental idle winding of the shade upon the roller to prevent the roller from losing its spring tension, and the shade is guided by the walls of the slots 18.

10 Having thus described the invention, what I claim as new and desire to secure by Letters Patent is:—

15 1. A window shade stop comprising a disc like body adapted to be secured to a window casing, and an integral extension portion projecting outwardly from one face of said disc like body and having a slot therein for the passage of one edge of a window shade.

20 2. A window shade stop comprising a disc like body adapted to be secured to a window casing, and having a central opening therein for the passage of a fastening element, and an extension portion projecting outwardly from one face of said disc like body and having a slot therein, one end of said slot terminating at the adjacent face of said disc like body for the passage of one edge of a window shade while the underside of said extension portion is adapted to be engaged by the free edge of a window shade to limit upward movement thereof.

25 35 In testimony whereof I affix my signature.
JACK C. STICH.
